LADY'S HAND BAG

Filed March 5, 1935

Helen C. Cowles

INVENTOR

UNITED STATES PATENT OFFICE

95,317

DESIGN FOR A LADY'S HAND BAG

Helen C. Cowles, New York, N. Y.

Application March 5, 1935, Serial No. 55,742

Term of patent 3½ years

To all whom it may concern:

Be it known that I, Helen C. Cowles, a citizen of the United States of America, residing in Manhattan, county of New York, and State of New York, have invented a new, original, and ornamental Design for a Lady's Handbag, of which the following is a specification, reference being had to the accompanying drawing, forming part thereof, wherein, the figure is a front perspective view of a handbag, showing my new design.

I claim:

The ornamental design for a lady's handbag, substantially as shown.

HELEN C. COWLES.
